UNITED STATES PATENT OFFICE.

CHARLES BERNHARD, OF NEW YORK, N. Y.

PROPELLING ATTACHMENT FOR SLEDS.

SPECIFICATION forming part of Letters Patent No. 243,195, dated June 21, 1881.

Application filed December 1, 1880. (No model.)

To all whom it may concern:

Be it known that I, CHARLES BERNHARD, a citizen of the United States, residing at New York, in the county and State of New York, have invented new and useful Improvements 5 in Propelling Attachments to Sleds, of which the following is a specification.

This invention consists in the combination, with a sled, of a propeller-wheel provided with 10 a series of spurs adapted to catch in snow or ice, a slide which forms the bearing for the shaft of the propeller-wheel, a spring for depressing said slide, a chain wheel or pulley mounted on the propeller-shaft, a crank-shaft mounted in 15 the upper part of the slide, a chain wheel or pulley mounted on this crank-shaft, and a chain or belt extending from this pulley to the pulley on the propeller-shaft, so that by manipulating the crank a rapid revolving motion 20 can be imparted to the propeller-wheel, and this wheel, together with the spurs, is free to yield to inequalities in the surface over which it passes. The propeller-spurs are mounted in guides and subjected to the action of springs, 25 so that each spur is adapted to yield independent of the rest and of the body of the propeller-wheel.

This invention is illustrated in the accompanying drawings, in which Figure 1 represents 30 a longitudinal vertical section in the plane $x x$, Fig. 2. Fig. 2 is a plan or top view. Fig. 3 is a transverse section in the plane $y y$, Fig. 2.

Similar letters indicate corresponding parts.

35 In the drawings, the letter A designates the seat of my sled, which is supported by the frame B and the runners C. On each side of the frame B is firmly secured an upright, D, and on the outside of this upright is situated 40 a slide, E, which forms the bearings for the propeller-shaft a and for the crank-shaft b . A spring, c, has a tendency to depress the slide E. The shafts a and b extend through slots d e in the upright D, so that they are able to rise 45 and fall with the slide, and that by the combined action of the slots and the shafts the slide is guided in its rising-and-falling motion. On one end of this shaft a is mounted the propeller-wheel F, and on its opposite end a chain 50 wheel or pulley, G. The propeller-wheel is provided with a series of spurs, f, which are

intended to catch in the snow or ice, and to propel the sled when a revolving motion is imparted to the propeller-wheel. On one end of the shaft b is mounted a crank, H, and on its 55 opposite end a chain wheel or pulley, I, which is connected to the chain wheel or pulley G by a chain or belt, g. The pulley I is of much larger diameter than the pulley G, so that by turning the crank H a rapid revolving motion 60 can be imparted to the propeller-wheel, and as the spurs of this wheel catch in the snow or ice, a rapid motion is imparted to the sled. By the action of the yielding slide E the propeller-wheel and its spurs are enabled to pass 65 over lumps of ice or stones or other inequalities without injury.

In the example shown in the drawings the spurs f are mounted in lugs h, which project from the sides of the propeller-wheel, and they 70 are subjected to the action of springs i, which have a tendency to force the points of the spurs outward to the position shown in Fig. 1. If one of the spurs strikes a stone or other hard substance its point recedes, and it is not 75 liable to become broken or otherwise injured. Instead of using the lugs h, the spurs may be inserted in holes in the periphery of the propeller-wheel or otherwise secured thereto, and subjected to the action of the springs i. 80

The cranks H may be so arranged that they can be driven by hand or by foot, or by both combined.

With the slide E is combined a stop, k, adapted to catch into a notch, t, therein, for 85 the purpose of retaining the slide in an upper position.

On the forward part of the sleigh are arranged two wheels, J, one on each side, which are mounted on bell-crank levers N, to which 90 are connected springs O, acting thereon with a tendency to hold the wheels off from the ground. When either the levers N is moved against the action of its spring O, the wheel J, which it carries, is brought into contact with the ground, 95 and by this means the sleigh can be steered in the desired manner.

What I claim as new, and desire to secure by Letters Patent, is—

1. A sled provided with a fixed upright, D, 100 projecting above and below the seat portion, and slotted at each end, in combination with

a vertically-movable spring-impelled slide, E, provided at its upper end with a crank-shaft extending through the upper slot in the standard, a spurred propeller-wheel the shaft of which extends through the lower slot in the standard and has its bearing in the end of the slide, and is movable therewith, and a driving mechanism connecting the crank-shaft and propeller-wheel shaft, all substantially as and for the purpose described.

2. The combination, with a sled, of a propeller-wheel provided with a series of spurs adapted to catch in snow or ice, a vertically-movable slide which forms the bearings for the shaft of the propeller-wheel, a spring for depressing said slide, a chain wheel or pulley mounted on the propeller-shaft, a crank-shaft mounted in the upper part of the slide, a chain

wheel or pulley mounted on this crank-shaft, and a chain or belt extending from this pulley 20 to the pulley on the propeller-shaft, all constructed to operate substantially as and for the purpose set forth.

3. The combination, with a sled, of a propeller-wheel, F, having at one side the lugs *h* 25 *h*, the spurs *f*, arranged to move in said lugs, and springs *i*, connected with the spurs and bearing against the lugs, all substantially as shown and described.

In testimony whereof I have hereunto set 30 my hand and seal in the presence of two subscribing witnesses.

CHAS. BERNHARD. [L. S.]
